CLAIM

I claim the ornamental design for the combined container and lid, as shown and described.

DESCRIPTION

FIG. 1 is a top perspective view of the subject combined container and lid;

FIG. 2 is a front side elevation view of the combined container and lid shown in FIG. 1;

FIG. 3 is a rear side elevation view of the combined container and lid shown in FIG. 1;

FIG. 4 is a first lateral side elevation view of the combined container and lid shown in FIG. 1, as seen from the left side of FIG. 1.

FIG. 5 is a second lateral side elevation view of the combined container and lid shown in FIG. 1, as seen from the right side of FIG. 1.

FIG. 6 is a top plan view of the combined container and lid shown in FIG. 1;

FIG. 7 is a bottom plan view of the combined container and lid shown in FIG. 1; and,

FIG. 8 is an exploded top perspective view of the combined container and lid shown in FIG. 1, with the lid removed and raised above the container.

The broken lines in the figures are included for the purpose of illustrating a portion of the subject combined container and lid, that forms no part of the claimed design.

1 Claim, 7 Drawing Sheets
